UNITED STATES PATENT OFFICE.

WILLIAM H. HAYS, OF CHICAGO, ILLINOIS.

DESIGN FOR A HALTER D.

SPECIFICATION forming part of Design No. 18,753, dated November 27, 1888.

Application filed September 27, 1888. Serial No. 286,602. Term of patent 7 years.

To all whom it may concern:

Be it known that I, WILLIAM H. HAYS, a citizen of the United States, residing at Chicago, in the county of Cook and State of Illinois, have invented and produced a new and original Design for a Halter D, of which the following is a specification, reference being had to the accompanying drawing, forming part thereof.

10 The figure is a plan view.

My new design for halter D has two novel features—the short legs b b and the curved or crowning cross-bar A. Legs b b are quite short, bringing members A and B quite close together as compared with halter D heretofore

in use, and the D presents a much neater appearance.

What I claim is—

The design for a halter D herein shown and described, consisting, essentially, of the short legs connecting the members A and B, the member A being curved inwardly, as shown.

In testimony whereof I sign this specification, in the presence of two witnesses, this 2d day of May, 1888.

WILLIAM H. HAYS.

Witnesses:

JAMES F. FORSYTH,
TINA V. CROWE.
